UNITED STATES PATENT OFFICE.

LORIN C. SPRINGER, OF HYDE PARK, ASSIGNOR OF ELEVEN-TWENTIETHS
TO CHANCY G. WRIGHT, OF CHICAGO, ILLINOIS.

MORSE REGISTER AND PERFORATOR.

SPECIFICATION forming part of Letters Patent No. 296,641, dated April 8, 1884.

Application filed March 3, 1883. (No model.)

To all whom it may concern:

Be it known that I, LORIN C. SPRINGER, a citizen of the United States, residing in Hyde Park, county of Cook, and State of Illinois, 5 have invented certain new and useful Improvements in Telegraph-Instruments, of which the following is a specification.

This invention relates to improvements in telegraph-instruments for producing Morse 10 characters by perforations in a paper or other ribbon.

The objects of this invention are to dispense with a multiplicity of instruments for automatic telegraphic purposes, by providing a single instrument adapted to operate as a perforator and a receiver, and yet involving great simplicity both in construction and operation; to provide an automatic telegraph-instrument adapted to perforate the paper ribbon with 15 the commonly known and used signs of the "Morse alphabet," to provide an automatic telegraph-instrument with means whereby it is adapted to automatically reproduce in the paper or other fibrous ribbon at the receiving-station perforations identical with those of the ribbon in the transmitting-instrument at the station from whence they were electrically transmitted, instead of reproducing said 20 signs in ink; to provide an automatic telegraph-instrument adapted to attain other important results necessarily following those above set forth, and involving certain details and modifications of construction, hereinafter 25 fully described. I attain these objects by devices illustrated in the accompanying drawings, in which—

Figure 1 is a side elevation of an automatic telegraph-instrument embodying my invention; Fig. 2, a central longitudinal section of 40 the same; Fig. 3, a plan view of the same; Fig. 4, a plan view of a modification of my invention, and Fig. 5 a side elevation of the same.

Similar letters of reference indicate the same 45 parts in the several figures of the drawings.

A A' represent the coils, B the armature, C the magnet, and D a portion of the pivoted lever, of the old and well-known "Morse transmitter," the frame E, carrying the clock-work

mechanism for actuating the paper ribbon, being broken away, for in my invention the paper ribbon may be actuated by this or any other suitable means. 50

Lever D is pivoted at substantially its center of length, so as to have a tilting or rocking movement, but is shortened as compared with its length in the Morse instrument, and has pivoted at its forward end a needle, a, the free end of which operates in coinciding perforations in guide-plates b c, secured to an arch, 55 d, on the frame E, between which guide-plates the paper ribbon e is drawn, as hereinafter described, by any suitable mechanism for that purpose. 60

Coil A is electrically connected with binding-post F, which should in turn be connected with a suitable battery, while coil A' is electrically connected with a metal L-shaped overhanging bracket, G, by a helix, f, and binding-screw g. 65

Secured on the lever D, which holds the armature, is a flexible metallic arm, h, insulated from the lever by a gutta-percha button, i, said arm being electrically connected by means of a wire, j, with the binding-post H, 75 and having contact when the lever is in the position shown in Fig. 2 with an adjustable screw, k, in the bracket G, with which it forms an electrical connection. 70

Lever D is held in the position shown in Fig. 2 by means of a coil-spring, I, one end of which is secured to an arm, l, depending from the lever D, and the other end to an adjustable screw passing through a post-supporting an L-shaped bracket, J, into which the lever D projects and operates between the usual stops, m n, common to the Morse receiver. 80

It should here be observed that to operate the instrument above described a key to make 90 and break the circuit is placed between the binding-post F and the battery, and that the binding-post H is connected with the opposing pole of the battery. With the above-described construction it will be understood that 95 a closed circuit will depress the armature and elevate the forward end of the lever D, which, lifting the needle a, will cause the needle to

perforate the paper ribbon passing through the guide-plates *b c*; but as the guide-plates are so close together as to barely permit the paper to pass freely through them, and the 5 needle and perforations quite small, it is obvious that some means must be provided for preventing the paper from tearing and the torn pieces and bits punched out by the needle from clogging the guides, as would necessarily occur if the circuit were closed long enough to cause the needle to make an elongated perforation or dash during the continuous passage of the ribbon through the guides. To obviate this difficulty is the purpose of 15 spring *h* and its peculiar electrical connection, the effect of which is to cause a very rapid vibratory movement of the lever *D* and a correspondingly-rapid reciprocation of the needle through the guide-plates, hence causing 20 the needle to punch out the paper as fast as presented to the needle in its passage through and between the guide-plates, and by this means I am enabled to produce perforations in the ribbon corresponding precisely 25 with the Morse alphabet. To produce these characters in perforations, and by the use of a single needle, it is absolutely necessary that the needle should be very rapidly reciprocated through the moving paper ribbon, or 30 the ribbon have, in addition to its longitudinal movement, a rapidly-vibrating one against the needle; hence I do not limit myself in producing the desired effect to the mechanism above described.

35 Instead of electrically vibrating the needle, as already described, the spring-arm *h*, its electrical connection, and the guide-plates *b c* may be dispensed with, and, as shown in Figs. 4 and 5, the needle be rigidly secured to a 40 yoke, 1, whence it extends downwardly through a perforation in a spring-tension guide, *e*, and a coinciding perforation in the lever *D*, said tension-guide being secured on top the lever and the ribbon passing between the guide and 45 lever, a lateral movement of the needle being prevented by passing it through a perforation in a bar, 3, of a frame, 4, in which the yoke 1 reciprocates, and to which is secured one or more hangers, 5, forming a bearing for 50 a sheave, 6, having upon one end of its rigid spindle an eccentric, 7, working in a rectangular opening in the yoke, said sheave being driven by a belt, 8, passing over a large drive-pulley, 9. In this construction it will be seen 55 that if the sheave 6 is rapidly revolved, the effect of the eccentric upon the yoke which rests thereon is to rapidly reciprocate the yoke, and with it the needle, the relative position of the needle and lever *D* being such 60 that when the end of the adjacent lever is depressed, as shown in Fig. 5, the end of the needle will not have contact with the ribbon; but when this end of the lever is elevated (see

dotted lines same figure) by closing the electric circuit the needle will then pass through 65 the ribbon and puncture it in the same manner as is done by the mechanism shown in Figs. 1, 2, and 3.

Instead of vibrating the needle, as shown in Figs. 4 and 5, the needle may be held rigid 70 and the lever *D* be vibrated, as before described, the effect of which would be to vibrate the ribbon against the needle and the attainment of the same practical result, or the guide-plates *b c* may be vibrated; hence I 75 do not limit myself to either of the mechanisms shown and described for producing perforations of the Morse characters in the ribbon, as it is immaterial which one is vibrated or what particular mechanism is employed to 80 obtain these vibrations.

Among the advantages of my invention is the reproduction at the receiving-office of the Morse characters in a perforated condition, thereby avoiding an auxiliary perforating-machine when it is desirable to transmit the same message upon one or more different lines, which may be done by running the ribbon from the receiving-instrument through the respective transmitting-instruments of those 90 lines, and besides this a permanent record not liable to fade out or to erasure is obtained by the receiving-office, and such a record as may at any time be sent to distant offices by rapidly running it through a transmitting-instrument. 95

Having now described my invention, what I claim, and desire to secure by Letters Patent, is—

1. The combination, with the perforating-needle and a guide for the ribbon, of the lever *D*, the coil *A A'*, and the vibrating arm *h*, said coil being intermittently electrically connected with the vibrating arm, the line-wire, the battery, and a suitable key, substantially 100 as described.

2. The combination, with the rocking-lever *D* and its central pivot, the armature *B*, and magnet *C*, of a perforating-needle directly attached to and actuated by the lever, said lever 110 being actuated by making and breaking an electric circuit connected therewith, substantially as described.

3. The combination, with suitable guides for the ribbon, and the lever *D*, having pivoted 115 thereto the perforating-needle, of the armature, the coil *A A'*, and the vibrating arm *h*, said coil being intermittently electrically connected with the vibrating arm, the line-wire, the battery, and a suitable key, all substantially as described. 120
